UNITED STATES PATENT OFFICE.

HENRY T. PAISTE, OF PHILADELPHIA, PENNSYLVANIA, ASSIGNOR TO H. T. PAISTE COMPANY, OF PHILADELPHIA, PENNSYLVANIA, A CORPORATION OF PENNSYLVANIA.

FUSE-CAPSULE.

1,112,313.

Specification of Letters Patent.

Patented Sept. 29, 1914.

Application filed June 5, 1913. Serial No. 771,953.

To all whom it may concern:

Be it known that I, HENRY T. PAISTE, a citizen of the United States, residing in Philadelphia, Pennsylvania, have invented 5 certain Improvements in Fuse-Capsules, of which the following is a specification.

One object of my invention is to provide a fuse capsule of the general type described and claimed in my application for U. S. 10 Patent 664,157 filed December 6, 1911, which shall be relatively inexpensive to make, shall be so constructed as to prevent discoloration of the mica cover of the fuse plug body when the fuse blows, and which shall have 15 one of its terminal portions disposed in a novel position relatively to the plug body. These objects and other advantageous ends I secure as hereinafter set forth, reference being had to the accompanying drawings, 20 in which,

Figure 1 is a side elevation of a fuse capsule constructed according to my invention; Fig. 2 is a vertical section of the capsule shown in Fig. 1; Figs. 3 and 4 are respectively plan views of the two ends of the capsule; Fig. 5 is a vertical section of a slightly modified form of the invention, and Fig. 6 is a vertical section illustrating one feature of my invention as applied to 30 a cartridge fuse.

The capsule constructed according to my invention is designed to be used with or as a part of a fuse plug whose body is shown in Fig. 1. This body has an annular form, being made of any suitable insulating material such as porcelain and having mounted within it a brass or other metallic shell 2 which in addition to an external part 35 pressed or otherwise formed into screw threads, has an internal portion 4 extending within the tubular cavity of said body 1. These two parts are connected by an annular shoulder portion 5 lying in a plane substantially at right angles to the center 40 line of the body 1, and the open end of said body is closed by a mica or other suitable transparent plate 6 held in place by an annular flanged metal cap 7. Lateral recesses 45 are provided in the body 1 adjacent its mica covered end, for the reception of tongues 8 whereby the shell 2 is held in place. This 50 particular fuse plug body is designed to receive a fuse capsule in the form of a somewhat elongated hollow porcelain body having a cylindrical portion or head 9 de- 55 signed to loosely fit within the threaded portion 3 of the shell 2, and having a second cylindrical portion 10 integral with the part 9. A shoulder 11 connects the two cylindrical surfaces of these parts, although 60 in case the fuse plug body should be made in the form shown and described in my application for patent above mentioned, this particular shoulder is replaced by the conically formed surface 11^a shown in Fig. 5. 65

The outer end of the head 9 of the capsule body is provided with a plate 12 constituting one terminal of the capsule and having connected to it one or more lugs 13, which as shown in Fig. 2 are expanded or bent 70 outwardly so as to engage or hold to the end portions of the cavity 14 of the capsule body. To the lug or lugs 13 I solder or otherwise electrically connect a fuse in the form of a strip or wire 15 of some metal or 75 alloy designed to melt at a predetermined temperature, and extend said fuse throughout said cavity, through a notch 16 formed in the relatively thin side adjacent the end of the part 10. Thereafter I extend said 80 fuse over the outside cylindrical surface of this part 10, bending it substantially at right angles across the shoulder 11 and carrying its end into a groove 17 formed in the side of the head 9 of the capsule. Both the notch 85 16 and the groove 17 are thereafter preferably filled in with some hard and relatively infusible insulating material such as a mixture of plaster of Paris and silicate of soda, after which a transparent disk 18 of mica or 90 other suitable material is placed over the open end of the cavity 14 and is held thereon by a flanged ring 19 retained in place by the above mentioned cementitious material. In addition to the filled notch 16, the end 95 of the part 10 of the capsule is provided with two or more notches 20 having grooved continuations 21 formed in the outside surface of said part, in order to permit of the escape of air and hot gases which may be 100 generated within the chamber 14 at the time the fuse 15 melts. These notches with their extensions co-operate with the cap formed by the ring 19 and disk 18 to provide air pas-

sages which open laterally out of the end of the capsule body, extend longitudinally of the capsule and discharge some distance from the end thereof.

5 Under conditions of use the capsule is introduced into the fuse plug body as shown in Fig. 1 so that the part 15^a of the fuse electrically contacts with the shoulder portion 5 of the metal shell 2. When this 10 fuse plug body with the capsule is screwed into a cut out block, receptacle or other suitable structure, the terminal plate 12 engages the central terminal of said socket while the threaded part 3 of the shell likewise electrically contacts with the similarly formed 15 threaded socket shell thus completing a circuit from the plate 12 through the body of the fuse 15 to the part 15^a thereof, thence to the shouldered part 5 of the shell 2, and 20 from the threaded portion 3 thereof to the threaded part of the socket. In case of the passage of an abnormal current through the circuit, the fuse 15 opens the same by melting in the well known manner, though owing 25 to the mica disk 18 upon the end of the part 10 of the capsule, the molten metal or smoke cannot be deposited on the mica coverpiece of the plug body but will be collected upon the cover 18 of the fuse capsule. 30 This latter may be thereafter removed and replaced by another capsule having its fuse intact.

It is to be noted that by providing the notch 16 rather than a perforation in the 35 edge of the open end of the part 10 of the capsule, the expense of manufacture is materially reduced, so that even with the added items of the mica disk 18 and its retaining ring 19, the cost of the plug still remains 40 relatively low.

In that form of my invention shown in Fig. 6 I have illustrated a cartridge fuse as equipped with a transparent cover similar to that employed as part of the capsule 45 above described. In this figure, the cylindrical body 26 of the cartridge fuse is usually made of a suitable length of a tube of insulating material having one end closed by a metal cap 27 and the opposite 50 end also closed by a transparent disk 18 of mica or other suitable material held in place by a flanged metal ring 19. In this case the fuse proper 28 extends between the metal cap 27 and the metal ring 19, being soldered 55 or otherwise electrically connected to both of these members. Under conditions of use, therefore, the flanged cap 27 and the ring 19 constitute the terminals of the fuse cartridge and electrically engage the terminals 60 of a suitable cut out block or other receptacle. In this case as before, the transparent cover plate 18 permits the inspection of the fuse 28 and at the same time prevents the discharge of molten metal when the fuse 65 melts. The ring and cap are held in place

by any suitable means, being shown for example, as having indentations 29 in their sides whereby a conical projection is forced into the adjacent parts of the fiber tube 26.

I claim:—

1. The combination in a fuse capsule of a tubular body of insulating material closed at one end and having two portions of different external diameters; a terminal plate on one end of said body; a conductor including a relatively fusible portion connected to the terminal within the body and extending therefrom over the external surface of said body; with a transparent cap normally closing the open end of said body; and means for holding the cap in place. 70

2. The combination in a fuse capsule of a tubular body of insulating material closed at one end and having two portions of different external diameters; a terminal plate on one end of said body; a conductor including a relatively fusible portion connected to the terminal within the body and extending therefrom over the external surface of said body; with a transparent cap 80 normally closing the open end of said body; and a flanged ring cemented to the body for holding the cap in place. 85

3. The combination in a fuse capsule of a tubular body of insulating material closed 95 at one end and including two portions of different external diameters, the portion of smaller diameter being open at its extremity and having a plurality of notches in its edge; a terminal plate on the end of the 100 body adjacent its large diameter portion; a conductor having a relatively fusible portion and connected to said terminal, extending through the body, through one of the notches in the edge of the smaller diameter 105 portion thereof and over the external surface of said body; with a cap closing the small diameter end of the body and co-operating with certain of the notches therein to form air passages. 110

4. The combination in a fuse capsule of a hollow body having two portions of different diameters and closed at its portion of large diameter; a terminal plate on the 115 end of the body adjacent said latter portion, the end of the small diameter part of the body being provided with notches extended from its edge in its external surface; a conductor having a relatively fusible portion and extending from the terminal plate 120 through the body, through one of said notches and over the external surface of the body; with a cap closing the open end of the body. 125

5. A fuse capsule consisting of a body of 125 insulating material having an open end provided with notches in its edge extended longitudinally of said body in the external surface thereof; with a cap closing said open end and having a portion extending 130

over the outside surface of the body and coöperating with the notches therein to form air passages opening laterally out of the end of the body, extending longitudinally of said body and discharging laterally at points distant from the end thereof; with a fuse in the body.

In testimony whereof, I have signed my name to this specification, in the presence of two subscribing witnesses.
